VERN J. CRISLER, OF CHICAGO, ILLINOIS

CUSHION PAD FOR GUNSTOCKS

Application filed December 12, 1929. Serial No. 413,470.

My invention relates to an improved construction of cushion pad for gun stocks by which the butt end of the stock is provided with a pad of soft, resilient material which may readily be applied to and removed from the gun stock without the use of tools of any kind so that pads of different size may be applied as desired, according to the purposes for which the gun is to be used. My invention further provides a novel form of device for attaching the pads to the gun stock, which at the same time permits the use of soft elastic material in the pad, for example India rubber, and yet securely holds the pad on the gun stock so that it cannot accidentally be displaced therefrom, or slip from the gun stock in use.

My invention will best be understood by reference to the accompanying drawings showing a preferred embodiment thereof in which

Fig. 1 shows in side elevation a part of a gun stock with my pad attached thereto,

Fig. 2 is an end view of the parts shown in Fig. 1,

Fig. 3 shows in end elevation to an enlarged scale, the retaining devices employed, this view being taken along the line 3—3 in Fig. 1,

Fig. 4 shows in end elevation to an enlarged scale the pad construction, this view being taken along the line 4—4 in Fig. 1,

Fig. 5 is a vertical sectional view to an enlarged scale through the butt end of a gun stock with the pad in place thereon, this view being taken along the line 5—5 in Figs. 2, 3 and 4, and

Fig. 6 is a horizontal sectional view to an enlarged scale of the butt end of a gun stock with the pad in place thereon, this view being taken along the line 6—6 in Figs. 2, 3, 4 and 5.

Similar numerals refer to similar parts throughout the several views.

As shown in Fig. 1, I illustrate the butt

portion of a gun stock at 10, to the butt end of which a retaining plate 11, preferably of cast metal for example brass or aluminum, is secured, which plate in turn holds the pad 12 in position to rest against the shoulder of the user of the gun.

As shown in Figs. 3, 5 and 6, the plate 11 is provided with a flange 13 around its edge, forming a recess 14 to receive a part of the pad 12. From the central portion of the rear face of the plate 11, a T-shaped extension 15 projects rearwardly, which extension is provided with an edge flange 15a extending in a plane substantially parallel with the front surface of the plate 11, in all directions from the extension 15, the outer edge of this flange 15a being sufficiently within the outline of the butt end of the gun stock 10, to permit the pad to surround it and enter the recess 14. The plate 11 is preferably secured to the stock 60 by screws 16 as indicated. The front face of the plate 11, is preferably a plane surface to facilitate securing the plate to the gun stock.

The pad 12 is preferably of soft resilient material which is substantially homogeneous throughout, for example soft India rubber and this pad has an outer conformation substantially the same as the outer conformation of the plate 11, which is preferably a 70 continuation of the surface of the butt end of the gun stock 10, so that the retaining plate and pad will present no projecting parts which extend beyond the surface of the gun stock. The pad 12 is provided in its 75 front portion, with a cavity 17 which as to size and shape is substantially a female counterpart of the T-shaped extension 15 of the plate 11. The pad is also provided with a rabbet or groove around the outer edge of 85 its front surface of substantially the size and form of the lip 13 on the plate 11, so that when the pad is applied to the plate 11, it is in close contact with the entire rear surface of the plate, and as a result is securely held 90

on the plate by the elastic nature of the pad and also by the fact that the close relation between the surface of the pad and the rear surface of the plate excludes practically all air from between the pad and the plate producing a vacuum cup effect between the pad and the plate when it is attempted to remove the pad from the plate, or when the pad is accidentally subjected to forces which might tend to remove the pad from the plate. As a result of this, when it is desired to remove the pad from the plate, although it may readily be done, the force required to remove it, is much greater than would be the case if it were necessary only to overcome the spring action of the material of the pad to clear the outer edge of the flange 15a on the T-shaped extension 15 of the plate 11. It will further be observed that the engagement of the pad with the lip or flange 13, produces an interlocking relation between the flange 13, the flange 15a and the material of the pad, materially increasing the tendency of the pad to retain its position on the plate 11. The flanges 13 and 15a form what is in effect a reentrant and continuous groove around the edge of the plate 11 to receive a corresponding bead formed around the front face of the pad 12, which bead, as well as the remaining material of the pad is preferably in non-stressed or neutral condition when the pad is in place on the plate, to the end that the full resilience of the pad may be available for cushioning effects.

With the construction described, I secure the benefit of soft elastic material in the pad, for example soft India rubber, which may be substantially pure gum rubber, which is advisable and desirable to cushion the recoil of the gun with which the pad may be used. At the same time, by forming the mounting plate 11 and the pad as described, I secure a substantial engagement between the plate and the pad, notwithstanding the soft condition of the latter, which insures the pad against accidental displacement and removal from the plate. When it is desired to remove the pad from the plate, it must be sprung outwardly away from the plate at some one point to disengage the pad from the flange 13 by stretching the material of the pad so that thereafter, the material of the pad may be stretched to pass around the flange 15a, the force exerted in removing the pad necessarily being great enough to not only produce the stretched condition of the pad referred to, but also to overcome atmospheric pressure on the pad tending to hold it on the plate. In placing the pad on the plate, it is preferably slid upwardly on the T-shaped extension 15 until the extension occupies nearly its proper position in the lower part of the pad, after which the upper part of the pad is stretched and worked around the upper part of the flange 15a and within

the flange 13. While the pad will not at once properly seat itself on account of air that may be trapped between it and the plate 11, I find that manipulating the pad with the fingers adjacent the plate 11, will soon expel the trapped air and that the pad will closely seat itself in contact with the T-shaped extension and the rear face of the plate 11 in the relation described above. My construction thus provides for positively retaining a pad of soft cushioning material on a gun stock, without the need of permanently attaching to the pad, material of any other kind to facilitate securing it to the gun stock, and it also provides a pad construction which may quickly and readily be removed from and placed on a substantial retaining plate, which is an advantage where a gun is to be used for different purposes and with different powder charges, since the pad may be produced in various thicknesses to meet all requirements, and both thin and thick pads may conveniently be provided for the same gun so that they may be interchanged to suit the convenience of the user.

The edge of the plate 11 may be polished and plated or provided with ornamentation of any desired kind, to impart a pleasing appearance to the gun stock to which it is secured.

While I have shown my invention in the particular embodiment above described, it will be understood that I do not limit myself to this exact construction as I may employ equivalents known to the art at the time of the filing of this application without departing from the scope of the appended claims.

What I claim is:

1. In a device of the class described, the combination of a metal mounting plate having substantially parallel front and rear faces, an edge flange extending rearwardly from said rear face and a T-shaped extension projecting rearwardly from the central portion of said rear face, said T-shaped portion having a continuous edge flange substantially parallel with said faces, and a cushioning pad of soft rubber having a cavity closely fitting said T-shaped portion and an edge rabbet closely fitting said edge flange, whereby said pad is in close interlocking engagement with the entire rear face of said plate, its rear extension and flanges.

2. In a device of the class described, the combination of a metal mounting plate having substantially parallel front and rear faces, an edge flange extending rearwardly from said rear face and a T-shaped extension projecting rearwardly from the central portion of said rear face, said T-shaped portion having a continuous edge flange substantially parallel with said faces, and a cushioning pad of soft rubber having a cavity closely fitting said T-shaped portion and an edge rabbet closely fitting said edge flange, where-

by said pad is in close interlocking engagement with the entire rear face of said plate, its rear extension and flanges, said T-shaped extension having a form similar to and of smaller size than the outline of said plate, whereby the outer surface of said pad is a continuation of the edge surface of said plate.

3. In a device of the class described, the combination of a mounting plate for attachment to a gun stock and having a flange-headed extension projecting from its rear face, and a pad of soft resilient material having a cavity in its front portion of substantially the size and shape of said extension, said pad and said plate having separable interengaging portions around their adjacent edges tending to hold said pad on said extension.

4. In a device of the class described, the combination of a mounting plate for attachment to a gun stock and having a flange-headed extension projecting from its rear face, and a pad of soft resilient material having a cavity in its front portion of substantially the size and shape of said extension, said pad and said plate having separable interengaging portions around their adjacent edges tending to hold said pad on said extension, said extension having an edge outline similar in form to and somewhat smaller than the edge outline of said plate.

5. In a device of the class described, the combination of a mounting plate having a re-entrant groove in the edge portion of its rear face, and a pad of soft resilient material having an edge bead fitting said groove.

6. In a device of the class described, the combination of a mounting plate having a re-entrant groove in the edge portion of its rear face, and a pad of soft resilient material having an edge bead fitting said groove with the material of said bead and pad in substantially unstressed condition.

7. In a device of the class described, the combination of a mounting plate having a re-entrant groove in the edge portion of its rear face, and a pad of soft resilient material having an edge bead fitting said groove, said groove being continuous around said edge portion.

8. In a device of the class described, the combination of a mounting plate having a re-entrant groove in the edge portion of its rear face, and a pad of soft resilient material having an edge bead fitting said groove, said plate having a plane front surface facilitating mounting it on a gun stock.

9. In a device of the class described, the combination of a mounting plate having a re-entrant groove in the edge portion of its rear face, a pad of soft resilient material having an edge bead fitting said groove, and devices for rigidly securing said plate to a gun stock.

10. In a device of the class described, the combination of a mounting plate for attach-

ment to a gun stock and having a flange-headed extension projecting from its rear face, a pad of soft resilient material having a cavity in its front portion of substantially the size and shape of said extension, said pad and said plate having separable interengaging portions around their adjacent edges tending to hold said pad on said extension, and devices for rigidly securing said plate to a gun stock.

In witness whereof, I hereunto subscribe my name this 4th day of December, A. D. 1929.
